UNITED STATES PATENT OFFICE

2,622,474

PORTABLE VISION TESTING DEVICE

Clay W. Keith, Tallahassee, Fla.

Application January 9, 1952, Serial No. 265,691

1 Claim. (Cl. 88—20)

1

The present invention relates to new and useful improvements in devices for testing the vision of applicants for motor vehicle driving permits and for otherwise conducting visual tests and more particularly to a portable cabinet for this purpose.

An important object of the invention is to provide a cabinet having removable alphabet or reading charts as well as color testing disks all illuminated by lamps in the cabinet to thus provide an intelligence test and a color blind test in a single vision testing device.

Another object is to provide a cabinet constructed in the form of a carrying case and having a removable top to afford access to the interior of the cabinet for changing the charts and providing the underside of the top with a cord holder on which an extension cord for the lamps may be coiled.

A still further object is to provide a device of this character of simple and practical construction, which is neat and attractive in appearance, relatively inexpensive to manufacture and otherwise well adapted for the purpose for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view;

Figure 2 is a vertical sectional view taken on a line 2—2 of Figure 3;

Figure 3 is a vertical transverse sectional view taken on a line 3—3 of Figure 2;

Figure 4 is a horizontal sectional view taken on a line 4—4 of Figure 2; and

Figure 5 is a diagram of the electric circuit for the lamps.

Referring now to the drawings in detail, wherein for the purpose of illustration I have disclosed a preferred embodiment of my invention, the numeral 5 designates a case of light weight metal, wood or other suitable material and of rectangular shape and provided with a carrying handle 6 at one side.

When placed in use the case rests on one end in an upstanding position and the opposite or upper end of the case is provided with a removable cover 7 also having a handle 8 and secured on the top of the case by conventional type of cabinet fasteners 9. A flat cord holder 10 is secured edgewise to the underside of cover 7 for winding an extension cord 11 thereon.

2

The cord 11 includes a plug 12 adapted to plug into an electric socket 13 at one side of the case, when the cord is removed from the holder 10 to connect a plurality of lamps 14 mounted on the inside of the case with a suitable source of current. The circuit 15 for the lamps is provided with a switch 16 mounted in one side of the case and preferably of the push button type.

The front and rear walls 17 and 18 of the case are open and over which are placed charts 19 and 20 each comprising a translucent panel 21 having indicia 22 painted or otherwise displayed thereon and which may comprise signs 23 formed of words 24, or letters of the alphabet 25, or direction arrows 26 suitable for testing the knowledge of a person of traffic signs and signals. The panels 21 are removably held in guide strips 27 on the inside of the front and rear walls.

The front wall of the case beneath the chart 19 is provided with a horizontal row of openings 28 in which are placed amber, red and green lenses 29, 30 and 31 to test color blindness.

By plugging in the cord 11 the lamps 14 may be energized to illuminate the charts 19 and 20 as well as the color disks 29, 30 and 31 to thus provide a vision test suitable particularly for conducting tests of applicants for driving licenses.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described my invention, what is claimed as new is:

A portable vision testing target device for testing the ability of persons to perceive various traffic signals, said target device comprising a substantially rectangular case having an upper removable end wall and means releasably securing the end wall thereto, said case including forward and rear vertically disposed walls each having a substantially rectangular opening therein, each of said openings having a pair of vertical edges, a pair of angle guide and retainer strips secured to the inner face of each forward and rear wall alongside of said vertical edges, translucent indicia bearing charts having vertical side

edges slidably engaging the guide strips and having their outer faces resting against the inner faces of said forward and rear walls, said charts having target means thereon representing various types of traffic signals and signs, said charts being removable from the case through the upper end thereof when said end wall is removed from the casing, illuminating means within the case for illuminating the charts, said forward wall having three horizontally spaced apertures below the opening in said forward wall, and red, green and amber color blindness testing lenses secured to said forward wall in registry with the apertures, whereby a person's ability to learn traffic signals and distinguish said various colors 15 may be determined.
